Letters Patent (Design No. 43) Dated Nov 12 1895.

The schedule referred to in these Letters Patent and making part of the same.

To all whom it may concern Be it known that I Ezra Ripley of the City of Troy Rensselaer County & State of New York have invented or produced a new design or figure to be carved upon stone patterns from which castings may be taken and thereby forming a stone of a certain peculiar form or shape and I do hereby declare that the following ^{and} ~~free~~ exact description of the same Fig 1 is a perspective view of my stone with the covering or figure work shown, the interior of which stone is one entire space for fuel. What I do claim therefore is the peculiar carving and combination of figure work and configuration in such a manner and combination with this particular form of stone and it is to be expressly understood that I claim nothing more.
